RAILWAY CAR

Filed March 21, 1924

UNITED STATES PATENT OFFICE

BYERS W. KADEL, OF BALTIMORE, MARYLAND

RAILWAY CAR

Application filed March 21, 1924. Serial No. 700,752.

This invention relates to railway cars and has among its objects to provide improvements in the door construction thereof. Another object is to provide improved means for supporting car doors and improved means for forcing such doors from one position of closure to another. With such objects in view the invention consists of the formation, combination and arrangement of parts as will be herein described and finally claimed.

In the accompanying drawings which show a preferred form of the invention, Figure 1 is a fragmentary side elevational view of the hopper portion of a twin hopper car of the well known type. Figure 2 is a fragmentary outer face view of one of the doors of such a car, this view being taken in the direction of arrow A, Figure 1. A door mechanism constructed in accordance with the principles of the present invention is shown as applied to the car in these two figures. Figure 3 is a transverse sectional view showing the mechanism, this view being taken on the line 3-3 of Figure 1. Figure 4 is a vertical sectional view through a portion of the mechanism, this view being taken on the line of 4-4 of Figure 2. Figure 5 is a vertical sectional view taken through the same on the line 5-5 of Figure 2. Figure 6 is a side elevational view of the hook or ledge members.

Referring to these drawings, the side of the car or in twin hopper car construction the end hopper sheet is denoted by numeral 1. This sheet may be carried around the bottom line of the car to form the usual slope sheet 2. A door-seating flange 3 may be formed along the edge of the side portion of this sheet in order to form sealing means for the lading. The hopper discharge opening is normally closed by means of the door 4 which is supplied with any suitable number of hinges such as indicated at 5. Such doors are preferably formed of steel plates and in twin hopper car construction they extend transversely of the car as indicated in the drawings and are arranged to fall open by gravity. Secured upon the outer face of the door is a stiffening member 6.

In twin hopper car construction where the door is usually separated at the center of the car to provide a space for the center sill construction, this member may comprise the usual door spreader. It is preferably formed of a modified channel or U section having a web 7 disposed in a plane substantially parallel with and removed slightly from the outer face of the door plate. From opposite edges of the web 7 the main flanges or webs 8 extend inwardly toward the door plate so that these flanges are disposed substantially at right angles to the plane of the door. The inner edges of the flanges or webs 8 terminate in return or outstanding flanges 9 which lie against the door plate and provide means through which the securing rivets 10 may be passed for securing the stiffener to the door plate. Such doors are ordinarily pushed shut by hand or by the foot and the present invention includes means for supporting such doors in closed position. A part of this means includes the fixed hook or ledge member 11 which is riveted to the end hopper sheet 1 by means of rivets 12. This member has a ledge 13 at its outer end adapted to be engaged by a latch 14 which is pivoted upon the door. The latch member 14 is disposed above the stiffener 6 and to the outer face of the stiffener there is secured an outer pivot bracket or housing member 15 this being secured to the web portion 7 of the stiffening member by means of rivets 16. This member 15 is of plate-like construction and occupies a plane parallel with and just outside of the web 7 and it forms an outer pivot bearing of the latch member 14, the pivot pin or rivet 17 having bearing therein. As an inner bearing or support for the pivot pin 17 an inner bracket 18 is provided, this lying against the outer face of the door and being secured thereto by means of the rivets 19. It will be noted that the latch member 14 has considerable freedom longitudinally of the pivot pin 17 between the outer pivot bracket 15 and the inner pivot bracket 18. It will also be noted that the pivot hole in the latch member is somewhat larger than would ordinarily be required for pivotal ac-

tion. These clearances are desirable in order to permit the ready functioning of the eccentric cam or locking device 20 shortly to be described. The pivot point of the latch

5 14 is at a considerably higher elevation than the ledge-engaging portion thereof and the latch is bent intermediate its ends so that the ledge-engaging portion lies substantially horizontal while the pivoted end thereof ex-

10 tends in a diagonally upward direction. This construction is particularly desirable as it gives better disposition of the parts and also adds to the economy and ease of operation of the construction.

15 When the door is pushed shut either by hand or by foot or by any other suitable means, the eccentric cam 20 having been rotated in counter clock-wise direction from the position shown in Figure 2, the latch can

20 be lifted and dropped into engagement behind the ledge 13 and the door thereby supported in at least partly closed position. It will be noted that when the cam 20 has been so rotated the ledge-engaging end of the

25 latch 14 may have considerable side-wise movement. It is in order that this movement may readily take place that the extra clearance is provided at the pivot end of the latch. Accordingly with the cam rotated

30 out of the way as above mentioned, when the door is first supported by the inter-engagement of the latch 14 and the ledge 13 it will be supported in a partly closed position as the weight of the door will take up all of

35 the play of the latch in the inward direction. The cam 20 is arranged with the customary peripheral eccentric locking face 21 adapted to bear down upon the upper edge of the latch to force it downwardly back of

40 the ledge 13 to thereby hold the latch against accidental release in service. The cam 20 is furthermore provided with a marginal shroud 22 which is adapted to fall behind the latch 14 when the cam is rotated. This

45 shroud is tapered from a lesser width at the line B to a greater width at the line C, see Figure 2, so that as the cam is driven in clock-wise direction into engagement with the latch 14 the tapered portion 22 will at

50 the same time by wedging itself between the door and the inner face of the latch 14 force the door to a more nearly closed position. The one member thus serves to force the door from a partly closed to a more com-

55 pletely closed position and serves to lock the latch in engagement with the ledge. The uppermost return or outstanding flange 9 of the door stiffener member may be slightly extended as shown to form an effective seat

60 for the back of the shroud 22.

In cases where the door is warped or buckled it may be forced shut by inserting a removable door-prying lever or bar such as 23 between the outer face of the latch and the inner edge of the stud 24 which is

formed upon the outer face of the ledge member 11. By applying force to the upper end of the bar 23 the door may be forcibly closed, if necessary to use external means. The outer end of the latch member is bent 70 outwardly at 25 to provide means for preventing the bar 23 from slipping off the latch when so used. In addition to cooperating with the removable lever for forcing the door shut the stud or laterally projecting portion 24 and the outwardly projecting portion of the latch may also cooperate with the lever to move the latch in an unlocking direction to release the door. To accomplish this the operator stands at the 80 side of the hopper to the rear of the door where he will not be struck by the lading when it is discharged and inserts the free end of the lever above the projection 24 and beneath the projecting portion of the latch. 85 The grasp end of the lever is then rotated upwardly forcing the latch from engagement with the hook. It is to be particularly noted that since the free end of the lever moves downwardly during this operation 90 the latch is free to slide off the lever. In this manner it will be perceived that the lever in no wise interferes with the gravity opening of the door.

I have thus described an embodiment of 95 my invention. Other embodiments are contemplated within the scope of the appended claims without departing from the spirit thereof.

What is claimed is

1. A railway car having a door, a fixed locking member and a latch member adapted for door supporting engagement therewith, one of said members carried by the car body and the other by the door, pivotal means for the latch member, and a movable locking member adapted to lock the two members in engaged positions, said locking member being also adapted to force the door from a preliminary position of closure to a 100 more completely closed position by bodily moving the latch member longitudinally of its pivotal axis.

2. A railway car having a door, a ledge member carried by the car body adjacent said door, a latch pivoted upon the door adapted for supporting co-operation with the ledge of said member, and a locking cam pivotally associated with the latch, the same having a face adapted to force the latch down 115 into engagement with the ledge and having another portion adapted to force the door toward its closed position.

3. A railway car having a door, a ledge member and a pivoted latch member, one carried by the car body and the other by the door, the latch being adapted for supporting engagement with the ledge of the said ledge member, the ledge-engaging end 125 of the latch being arranged for movement 130

at right angles to the plane of swing of the latch, and means for forcibly effecting such movement.

4. A railway car having a door, a ledge member and a pivoted latch member, one carried by the car body and the other by the door, the latch member being adapted for supporting engagement with the ledge of the said ledge member, the ledge-engaging end of the latch being arranged for movement at right angles to the plane of swing of the latch, and means adapted to contact one side of the latch for forcing the door from a partly closed to a more completely closed position.

5. A railway car having a door, a ledge member and a pivoted latch member, one carried by the car body and the other by the door, the latch member being adapted for engagement with the ledge of the ledge member to hold the door in a closed position, and wedging means arranged to exert pressure between the door and the latch member to force the door to a more completely closed position by moving the latch member in a plane at substantially right angles to that of the normal plane of pivotal motion thereof.

6. A railway car having a door, a ledge member affixed to the car body, a latch pivoted upon the door and normally adapted to swing in a plane substantially parallel to that of the door into engagement with the ledge of the ledge member to hold the door in closed position, and means rotatable between the door and the latch adapted to cause said latch to hold the door in different positions of closure.

7. A railway car having a door, a stiffening member attached to the outer face of the door, the same embodying a channel shaped section arranged with its web in a plane substantially parallel with the outer face of the door and removed slightly therefrom, a ledge member provided upon the car body and a latch member pivoted upon the door and adapted for supporting co-operation with said ledge member, and a pivot bracket for the latch the same lying against and being secured to the outer face of the web of said channel.

8. A railway car having a door, a stiffening member mounted upon the outer face of the door, the same being formed of a member of channel section, the web thereof being disposed in a plane substantially parallel with the outer face of the door and removed slightly therefrom, a ledge member provided upon the car body and a latch member pivoted upon the door, said latch being adapted for supporting co-operation with the said ledge member, the said latch being arranged above the said channel section and being mounted thereupon for swinging movement in a plane substantially parallel

with that of the door, the mounting means embodying a bracket secured to the face of the door and a housing portion secured to the said channel.

9. A railway car having a lading discharge opening, a door for closing said opening, a fixed hook carried by the car body, and a pivoted latch mounted on the door co-operable with said hook for supporting the door in closed position, said hook being fashioned on its outer face with a projection forming a fulcrum for a removable door prying lever whereby the door may be forced to closed position.

10. A railway car having a lading discharge opening, a door for closing said opening, and means for supporting the door in closed position involving a hook affixed to the car body and a latch pivotally secured to the door, the fixed hook being provided with an outwardly projecting portion adapted to form a fulcrum for a removable prying lever, said lever being operable between the projection and outer end of the latch for prying the door to closed position.

11. A railway car having a lading discharge opening, a hinged door for closing said opening, a hook mounted on the car body, a latch pivotally secured to the door and extending outwardly beyond an edge thereof for cooperating with the hook to support the door in closed position, and a plate member overlapping the latch adjacent the said edge of the door constituting means for limiting movement of the latch outwardly away from the door, said plate further constituting a pivotal support for the said latch.

12. A railway car having a door for closing a lading discharge opening, said door being adapted to swing to open position under the influence of gravity, a latch pivotally mounted on the door and extending outwardly beyond an edge of the latter, and a door locking member rigidly affixed to the car body and provided with a ledge for engagement by the latch to support the door in closed position, said latch having a portion extending laterally outward beyond said ledge, said locking member projecting beyond the lading discharge opening in the direction of opening movement of the door and being provided on its outer side with a lateral projection affording a fulcrum for a removable lever, said fulcrum being in advance of said ledge in the direction of opening movement of the door, whereby said lever when in engagement with said fulcrum and the outwardly projecting portion of the latch may be rotated to effect an unlocking movement of the latch.

13. In car door mechanism, the combination with a hinged door adapted to move to open position under the influence of gravity, of means for supporting the door against

- opening movement, said means involving a latch pivotally mounted on the door and projecting outwardly beyond an adjacent edge of the latter, and a shouldered member rigidly secured to the car body and adapted to be engaged by the latch, said shouldered member being provided below its latch engaging portion with an outwardly extending projection forming a fulcrum for 10 a removable door prying lever, the latter being adapted to cooperate with the fulcrum and outwardly projecting portion of the latch to force the door towards closed position.
- 15 14. A railway car having a hinged door for closing a lading discharge opening, a flanged stiffening member secured to the outer face of said door, said member having a portion substantially parallel with and spaced outwardly from the door, a shouldered member rigidly secured to the car body, a latch member pivotally mounted upon the door and cooperable with the shouldered member to support the door in closed 20 position, a plate member secured to the outwardly spaced portion of the stiffening member and projecting laterally therefrom toward the hinge axis of the door in overlapping relation to the outer face of the door, said latch being interposed between said plate member and the door, and means connected to said plate member above the stiffening member affording a pivotal support for said latch.
- 25 15. A railway car having a door for closing a lading discharge opening, a flanged stiffening member secured to the outer face of said door, said member having a portion substantially parallel with and spaced outwardly from the door, a shouldered member rigidly secured to the car body, a latch member pivotally mounted upon the door and cooperable with the shouldered member to support the door in closed 30 position, and a pivoted cam for locking the latch member in door supporting position, a plate member overlying the outer face of the latch member and cam and rigidly secured to the outwardly spaced portion of said stiffening member, and means connected to said plate member affording pivotal supports for said latch member and cam.
- 35 16. A railway car having a door for closing a lading discharge opening, a flanged stiffening member secured to the outer face of the door, said member being provided with a portion substantially normal to the door and with a portion spaced outwardly from and substantially parallel thereto, a 40 shouldered member carried by the car body, a latch pivotally mounted upon the door and arranged to engage said shouldered member to support the door in closed position, said latch being disposed above the normal portion of the stiffening member, a

plate member overlying the outer face of said latch and rigidly secured to the outwardly spaced portion of said stiffening member, and means connected to said plate member affording a pivotal support for the 70 said latch.

17. A railway car having a door for closing a lading discharge opening, said door being adapted to swing to open position under the influence of gravity, a latch pivotally mounted on the door and extending outwardly beyond an edge of the latter, and a shouldered member rigidly affixed to the car body adapted to cooperate with the latch to support the door in closed position, the outer end of said latch being fashioned with a laterally projecting portion, said shouldered member having a projecting portion affording a fulcrum for a removable lever, said lever being adapted to engage the latch between its offset portion and the outer face of the shouldered member whereby the door may be forced toward closed position.

18. A railway car having a door for closing a lading discharge opening, said door being adapted to swing to open position under the influence of gravity, a latch pivotally mounted on the door and extending outwardly beyond an edge of the latter, and a shouldered member rigidly affixed to the car body adapted to cooperate with the latch to support the door in closed position, said shouldered member being provided with a projecting portion affording a fulcrum for a removable lever adapted to engage the outwardly projecting portion of the latch to force the door to a fully closed position, the outwardly projecting portion of said latch being provided with means for limiting movement of the lever longitudinally of the latch.

19. A railway car having a door for closing a lading discharge opening, said door being adapted to swing to open position under the influence of gravity, means for supporting the door against opening movement involving a latch pivotally mounted on the door and projecting outwardly beyond the adjacent edge of the latter, and a shouldered member rigidly secured to the car body, the outwardly projecting portion of the latch being integrally formed with an offset portion, said shouldered member being provided with a laterally projecting portion affording a fulcrum for a removable lever, said lever being adapted to engage the outwardly projecting portion of said latch between the offset portion thereof and the outer face of the shouldered member whereby the door may be forced to closed position.

20. A railway car having a door for closing a lading discharge opening, said door being adapted to swing to open position under the influence of gravity, means for sup-

porting the door against opening movement involving a latch pivotally mounted on the door and extending outwardly beyond the adjacent edge of the latter, and a shouldered member rigidly secured to the car body, said latch and shouldered member being adapted to cooperate with each other to support the door in closed position, the outer end of said latch terminating in a portion projecting in the direction of opening movement of the door, said shouldered member being provided with a laterally projecting portion affording a fulcrum for a removable lever, said lever being adapted to engage the latch between the projecting portion thereof and the outer face of the shouldered member whereby the door may be forced toward closed position.

21. A railway car having a door for closing a lading discharge opening, said door being adapted to move to open position under the influence of gravity, means for supporting the door in closed position involving a shouldered member rigidly secured to the car body and a latch pivotally mounted on the door having a portion projecting outwardly beyond a side edge thereof engageable with the shouldered member, said latch terminating in a portion disposed substantially parallel to and spaced from the outer face of the shouldered member, said shouldered member being provided on its outer face with a lateral projection affording a fulcrum for a removable lever, the latter being adapted to engage the latch between the end portion thereof and the outer face of the shouldered member whereby the door may be forced toward closed position.

In testimony whereof I affix my signature.
